(57) **CLAIM**

The ornamental design for a cup holder, as shown and described.

DESCRIPTION

FIG. 1 is a front, top, and left side, perspective view of a cup holder in a use position according to my new design.

FIG. 2 is a top plan view thereof.

FIG. 3 is a bottom plan view thereof.

FIG. 4 is a front elevation view thereof.

FIG. 5 is a rear elevation view thereof.

FIG. 6 is a left side elevation view thereof.

FIG. 7 is a right side elevation view thereof; and,

FIG. 8 is a perspective view thereof in a storage position. The broken lines and areas within them in FIG. 3 depict portions of the cup holder that form no part of the claimed design.

1 Claim, 4 Drawing Sheets
